UNITED STATES PATENT OFFICE.

BENJAMIN F. BROWN, OF PROVIDENCE, RHODE ISLAND.

SCARF-RING.

SPECIFICATION forming part of Letters Patent No. 236,874, dated January 25, 1881.

Application filed June 5, 1880. (No model.)

To all whom it may concern:

Be it known that I, BENJAMIN F. BROWN, of the city and county of Providence, and State of Rhode Island, have invented a new and useful Improvement in Scarf-Rings; and I hereby declare that the following is a full, clear, and exact description of the same, reference being had to the accompanying drawings, forming part of this specification.

10 The object of this invention is to so construct a scarf-ring that the same will be retained in place and secure the scarf.

The invention consists in the peculiar and novel construction of the scarf-ring, by which 15 the same can be readily secured to or form part of the collar-button, as will be more fully set forth hereinafter.

Figure 1 is a perspective view of a scarf-ring in which the back plate is hinged to the 20 front and provided with a snap, so that the front can be raised and passed over the scarf. The rear plate is provided with a suitable slot, so that the scarf-ring can be secured to the collar-button. Fig. 2 is a view of a scarf-ring, to 25 the back plate of which one part of a separable button is secured, the shoe of the button being shown below the figure. Fig. 3 represents a solid scarf-ring or loop, forming the front part of a separable button. Fig. 4 is a 30 view of a scarf-ring the rear of which is provided with a fixed button. Fig. 5 is a view of a collar and tie secured by a scarf-ring secured to or attached to a collar-button. Fig. 6 is a perspective view of a scarf-ring suspended 35 by a slot from a collar-button.

The essential feature of the invention consists in connecting a scarf-ring and collar-button so that the button will hold the scarf-ring in its proper place.

40 In the drawings, *a* is the front portion of a scarf-ring; *b*, the rear portion. The two may

be formed in one piece, or they may be hinged and secured by any desired means, Figs. 1 and 2 showing the ring so hinged to the back plate, and the other figures showing solid 45 rings.

c represents the collar-button, which, as shown in Figs. 1 and 6, may be entered into any suitable slot made in the rear plate, *b*, of the scarf-ring, so that the ring is suspended 50 from the button.

d is the shank of a button, and may be provided with any suitable device, so as to form a separable button, which can be readily connected with or disconnected from the shoe *e*; 55 or the ring, shank, and shoe may be permanently secured, as shown in Fig. 4.

The shank *d* may be secured to any part of the back plate, or the extension *f* (shown in Fig. 6) may extend in any direction desired, 60 and may be provided with a slot, as shown in broken lines in that figure, or have the shank, or, if desired, the shank and shoe, secured to the extension *f*.

A scarf-ring forming part of a separable or 65 other collar-button, or arranged so that it can be readily secured to the button, forms a convenient and desirable device or ornament.

Having thus described my invention, I claim as new and desire to secure by Letters 70 Patent—

1. The combination, with a scarf-ring, of a collar-button constructed to hold the scarf-ring in place, as described.

2. The combination, with the scarf-ring, of 75 the shank *d* and shoe *e*, constructed to secure the scarf-ring to the collar, as described.

BENJAMIN F. BROWN.
